(57) **CLAIM**

The ornamental design for a code reader with clip as shown and described.

DESCRIPTION

FIG. 1 is a front, right and top perspective view of a code reader with clip, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view of the code reader with clip of FIG. 3, taken along section line 9-9 as depicted in FIG. 3.

The broken lines shown in the drawings are included for the purpose of illustrating portions of the code reader with clip that form no part of the claimed design.
